UNITED STATES PATENT OFFICE.

EDWIN S. FRIDHAM AND PETER L. JENSEN, OF OAKLAND, CALIFORNIA, ASSIGNEES
TO THE MAGNAVOX COMPANY, OF SAN FRANCISCO, CALIFORNIA, A CORPORATION
OF ARIZONA.

RADIO RECEIVING APPARATUS.

Application filed November 8, 1924. Serial No. 743,567.

This invention relates to radio receiving apparatus.

The object of the invention is to facilitate tuning of a receiving set employing one or 5 more stages of radio frequency amplification, and wherein capacity or inductance of the amplifying circuits is required to be tuned to the antenna circuit. This necessitates manipulation of a plurality of tuning 10 devices, and where there are two stages of amplification the operator is confronted with the problem of keeping all three circuits in proper resonance throughout the wave length scale when endeavoring to tune 15 in on a designated station.

In and by the present invention we provide a unit control for simultaneously tuning said circuits so that the time and effort required in tuning is materially lessened. 20 In other words, instead of providing three separate controls for tuning purposes, a single control is provided, which simultaneously actuates two or more tuning devices, keeping all of the different circuits to be 25 tuned in resonance at all times.

By way of illustrating one manner of carrying out our invention, reference is made to the accompanying drawings, in which—

30 Fig. 1 shows a plan view of a receiving set embodying our invention;

Fig. 2 shows a front elevation of the same;

Fig. 3 shows a vertical sectional view through the middle portion of the panel;

35 Fig. 4 shows a diagram of the circuits employed in connection with the specific form of apparatus herein illustrated.

While our invention is not concerned with any particular wiring diagram, it will assist 40 in an understanding of the invention to refer generally to Fig. 4, wherein R^1 and R^2 indicate the radio-frequency amplifying tubes, D the detector tube, and A^1 and A^2 the audio-frequency amplifying tubes. V^1 , 45 V^2 , and V^3 designate the variometers used in the three tuning circuits. The variometers may be of any desired form, and in the present apparatus we show them as consisting of flat coils with the stator 10 upon a panel 11 and a rotor 12 carried upon a shaft 13, which shafts are journaled upon said panel 11. The three shafts upon which the rotors 50 of the three variometers are carried are connected together for joint rotation. There

are a variety of ways of effecting such joint 55 rotation, and the one herein described and illustrated is to be considered merely as a preferred form. Fixed upon each of the shafts 13 is a pinion 14. Meshing with the pinion 14 on the central shaft are two 60 toothed racks 15, one rack being arranged at the top of said pinions and the other at the bottom thereof, and the two racks extending in opposite directions and meshing at their outer ends with the pinion on the 65 adjacent shaft. These racks are supported at each end upon a roller 16, which maintains them in mesh with the adjacent pinion. Lost motion or back-lash of the racks is prevented by a small torsion spring 17 bound on 70 each of the two outer shafts 13. One end of the spring is anchored to the shaft, and the other end to a post 18 adjacent the shaft. The two springs are wound in opposite directions and constantly exert a small tension, 75 tending to turn the two outer shafts in opposite directions, thus maintaining a constant tension or friction upon the two outer shafts which serves to take upon any lost motion or play that may occur in the gear- 80 ing which connects the three shafts together.

The central shaft 13 is actuated by a knob 19, carrying a pinion 20 meshing with a gear 21 fixed on said central shaft. The central 85 shaft is preferably provided with a pointer 22 co-operating with a graduated dial on the front of the cabinet which houses the set.

Turning the knob 19 will impart motion to all of the three shafts simultaneously, and 90 on account of the arrangement of the toothed racks the two outer shafts will be turned in a direction opposite to the central shaft. The purpose of this opposite rotation is to minimize magnetic coupling between the three variometers, such as would 95 occur if all of the variometers had their rotors in parallel planes. It will be noted that the stators of the three variometers are in parallel planes, and at zero position the 100 three rotors will be parallel.

However, due to the fact that the rotor of the central variometer turns in one direction and the rotors of the two other variometers turn in the opposite direction, the 105 three rotors do not occupy parallel positions at any points except zero and 180°. Therefore, the likelihood of mutual inductance

arising at any point within the extreme limits of the wave length scale is effectually overcome.

We find that if the three tuning circuits 5 are once placed in proper resonance, they will remain so throughout the wave length scale. Therefore, to bring these circuits into resonance, we provide a variable condenser 23 for each of the tuning circuits, by 10 means of which the capacitance of the circuits may be adjusted. These condensers are preferably placed within the cabinet, and while adjustable, they are not intended to be manipulated by the operator. The adjustment is a fixed one, and is intended to be 15 done by an expert at the factory or place of assembly, and once properly set, the circuits will remain in resonance and the operator has merely to concern himself with the manipulation of the variometers, in order to 20 bring the instrument into tune with various wave lengths.

The unit control of a plurality of tuning devices can also be applied to receiving sets 25 of the neutrodyne type. In such cases the three variable condensers for the major tuning operation are connected together for joint movement. For local reception no further adjustment of the circuits will be 30 necessary, but for fine tuning each circuit should be provided with an individually adjustable condenser in addition to the unit control condensers, whereby the product of 35 the inductance and net capacity may be made the same for each circuit. The indi-

vidually adjustable condensers likewise permit circuits to be placed in resonance and compensate for variations in the capacity of different tubes.

What we claim as new and desire to secure by Letters Patent is:

1. In a radio receiving apparatus employing tuned radio frequency, a variometer for the antenna circuit and a variometer for each of the two radio frequency amplifying 45 circuits, a panel on which said variometers are arranged, a pinion on the shaft of each rotor of said variometers, a pair of toothed racks meshing with the pinion on the rotor of the intermediate variometer, said racks 50 extending in opposite directions and meshing with the pinions of the variometers at either side, in such manner as to cause opposite movement of the rotors at the side with respect to the rotor of the intermediate 55 variometer.

2. In a radio receiving apparatus, a plurality of tuning circuits, a variometer in each circuit, each of said variometers including a rotor, a shaft for each rotor journaled 60 on a panel, a pinion on each shaft, a toothed rack connecting pinions of adjacent shafts together for joint rotation in opposite directions, and a tension spring on certain of said shafts, tending to turn them in opposite directions, whereby to take up slack in the connections. 65
